(57) **CLAIM**

The ornamental design for a parking pay station, as shown and described.

DESCRIPTION

FIG. 1 is a top, front, right perspective view of a parking pay station, showing our new design;

FIG. 2 is a top, back, left perspective view thereof;

FIG. 3 is a front elevational view thereof;

FIG. 4 is a back elevational view thereof;

FIG. 5 is a left side elevational view thereof;

FIG. 6 is a right side elevational view thereof; and,

FIG. 7 is a top plan view thereof.

The broken lines shown in the drawings represent portions of the parking pay station that form no part of the claimed design. The letters, numbers, and symbols on the buttons and panels shown in FIGS. 1 and 3 and the small circles in FIGS. 1, 3, and 7 are in broken lines and form no part of the claimed design.
